UNITED STATES PATENT OFFICE.

FÉRNUAND RADELET AND EDMOND BONNET, OF BRUSSELS, BELGIUM.

SPIKE FOR RAILS.

Application filed June 15, 1920. Serial No. 389,225.

To all whom it may concern:

Be it known that FÉRNUAND RADELET and EDMOND BONNET, subjects of the King of the Belgians, residing at Brussels, Belgium, 5 have invented new and useful Improvements in Spikes for Rails, of which the following is a specification.

In our application for Letters Patent Ser. No. 354068 filed on the 26th January 10 1920 we have disclosed railway spikes and screws having a rail engaging surface inclined at 135° or more to the stem. With such an angle, instead of exerting on the spike or screw a pull directed longitudinally 15 of its stem, the vibration of the rail exerts a lateral pressure on the head of the spike or screw and tends to swing same and force the stem against the inner wall of its seat, whereby its adherence to the sleeper is considerably increased. This action obtains 20 whether the spike or screw is driven vertically or at an angle to the sleeper, the essential condition being that in use the rail engaging surface be at an angle of 45° or more to 25 the horizontal.

The present invention contemplates improvements in the spikes according to our said application Ser. No. 354068 and has for its object further to increase their resistance to an outward pull and to improve the conditions under which they work, whatever be the position they must assume in order that their rail engaging surface shall be inclined to the required extent.

An important feature of our invention consists in giving to the rear face of the head of the spike (i. e. to the face remote from the rail engaging surface) such an inclination that said rear face rests on the sleeper 40 when the spike is positioned in the same. The head of the spike thus bears on the surface of the sleeper and the area of its rear face is added to the contact area between the stem and the sleeper, i. e. to the working area of the spike.

The efficiency of our improved spikes may also be increased by providing a set of teeth or projections on the front and rear faces of the stem at the points where the lateral motion imparted by the vibration of the rail tends to force the stem into the material of the sleeper.

The head of the spike may also be provided with a projection or hook adapted to engage the foot of the rail only after the

spike has assumed, under the action of excessive vibrations or stresses, such an inclination that it can no longer be pulled out of its seat by a vertical pull on said hook.

In the accompanying drawings which illustrate, by way of example, various embodiments of the invention:

Fig. 1 is an elevation of a spike according to the invention which is driven slantwise into the sleeper;

Fig. 2 is a similar view showing the spike anchored in the sleeper;

Fig. 3 likewise shows the head of a vertically driven spike;

Fig. 4 is an elevation of the head of a 70 slightly modified spike;

Referring to Fig. 1 the front or rail engaging surface *f* of the head of the spike *m* has such an inclination that it is adapted to form when in use, an angle of at least 45° with the horizontal. The rear face *n* of the head of the spike is inclined in the opposite direction at such an angle that it is adapted to rest, when in use, on the surface of the sleeper *o*. As shown in the drawing it is desirable that, when the spike has been driven longitudinally, the face *n* should be slightly inclined to the horizontal (Fig. 1) so that a heavy hammer blow on the front part of the head would secure the spike in position 85 with the face *n* bearing against the sleeper (Fig. 2). Henceforth the face *n* will give rise to an additional resistance and will co-operate with the stem in opposing the lateral motion the rail tends to impart thereto.

As has been explained in our application Ser. No. 354068 aforesaid, this lateral motion is in the nature of a rotation and results from strains which at first tend to force into the material of the sleeper both 95 the lower portion of the front face and the upper portion of the rear face of the stem of the spike. In order to increase the adherence of the stem to the walls of its seat it is advantageous to provide the lower portion of 100 the front face *p* and the upper portion of the rear face *q* with a set of teeth *r* which engage the material of the sleeper and become anchored therein. In use the strains exercised by the rail only tend to increase the 105 hold of the teeth on the sleeper. Preferably the teeth *r* do not extend over the entire length of the stem in order to avoid the formation of gaps where the stem tends to move away from the walls of its seat.

The spike illustrated in Fig. 3 is similar to that shown in Figs. 1 and 2, but the inclination of the face n is such that said face will rest on the sleeper after the spike has 5 been driven vertically therein.

In Fig. 4 is shown a spike which differs from those described above by the provision of a projection or hook s at the upper end of the rail engaging surface f . This projection 10 does not come into contact with the foot l of the rail and it is adapted to engage the same only if, as the result of excessive strains, the spike should assume a strongly inclined position in the sleeper, in which 15 event the projection s would act as a safety device. On account of the considerable inclination of the stem the vertical strains exercised on said projection by the foot of the rail would only cause the front face of the 20 stem to press against the material of the sleeper.

Having now described our invention, what we claim as new and desire to secure by Letters Patent is:

25 1. A railway spike comprising a stem, and a head having a straight rail-engaging surface at an angle of at least 135° to said stem

and a flat rearwardly extending surface adapted to bear against the sleeper.

2. A railway spike comprising a stem and 30 a head having a straight rail engaging surface adapted to transmit the greater part of the vibration of the rail to the stem in a lateral direction and a flat rearwardly extending surface adapted to co-operate with the 35 sleeper in opposing a lateral movement of the head.

3. Railway spikes comprising a stem, a set 40 of teeth extending only on the lower portion of the front face of said stem, a set of teeth extending only on the upper portion of the rear face of said stem, and a head having an inclined rail engaging surface and a rearwardly extending surface adapted to engage the 45 sleeper.

In testimony whereof we have signed our names to this specification in the presence of two subscribing witnesses.

FÉRNAND RADELET.
EDMOND BONNET.
